UNITED STATES PATENT OFFICE.

FRANK SIMONS, OF BUFFALO, NEW YORK.

LUGGAGE-CARRIER FOR VEHICLES.

SPECIFICATION forming part of Letters Patent No. 752,004, dated February 9, 1904.

Application filed December 17, 1902. Serial No. 135,602. (No model.)

To all whom it may concern:

Be it known that I, FRANK SIMONS, a citizen of the United States, residing at Buffalo, in the county of Erie and State of New York, have 5 invented certain new and useful Improvements in Luggage-Carriers for Vehicles, of which the following is a specification.

This invention relates to luggage-carriers for vehicles, but more particularly to that 10 class of such carriers as are adapted for use on bicycles.

The object of my invention is to provide a 15 cheap, light, and durable carrier of this class which can be conveniently and quickly attached to or detached from the bicycle, which is adjustable to carry parcels and books of different sizes, and which can be rolled into a very small space and conveniently carried in the pocket of the rider when not in use.

20 Other objects are to provide a luggage-carrier which can be conveniently supported on the handle-bars of a bicycle so as to be out of the way of the rider, which will not interfere in the least with the free and easy steering of 25 the bicycle, and wherein a bag may be conveniently held to carry small articles in bulk.

With these objects in view the invention 30 consists of two vertical straps doubled to form open-loop supporting-straps and two closed horizontal loop-straps, to which the vertical 35 loop-straps are riveted or otherwise secured. The ends of the vertical straps are riveted or otherwise secured to the upper horizontal loop-strap. Each strap is provided with two 40 buckles to permit of adjusting the carrier to the size of the article to be carried.

It also consists in the peculiar construction, arrangement, and combination of parts, as 45 will be hereinafter more particularly described, and pointed out in the appended claims.

In the drawings, Figure 1 is a perspective 50 view of my improved luggage-carrier attached to the handle-bars of a bicycle. Fig. 2 is a similar view showing the same adjusted to support a small book and a large book at the same time. Fig. 3 is also a similar view of the carrier; but in this instance a bag is held in the same. Fig. 4 is a horizontal section 55 taken on line y y , Fig. 2. Fig. 5 is a per-

spective view of a modified form of my invention looking at the carrier from the rear. Fig. 6 is a horizontal section taken on line z z , Fig. 5. Fig. 7 is an enlarged detached perspective view of the retaining-clip, which braces the steering-head. 55

Referring to the drawings in detail, like numerals of reference refer to like parts in the several figures.

The numeral 1 designates the steering-head 60 of a bicycle, and 2 the handle-bars thereof.

The carrier, considered as a whole, is designated by the numeral 3 and comprises two vertical supporting-straps 4 and 5, doubled upon themselves to form open-loop supports 65 for the articles to be carried. To the ends of these straps a horizontal loop-strap 6 is riveted or otherwise secured, and between the ends and the bottom of the open-loop straps 4 and 5 a second horizontal loop-strap 7 is riveted or 70 otherwise secured. Secured to the upper horizontal loop-strap, preferably at the points of connection thereof with the rear strands of the vertical open-loop straps, are two small loops 8, which are adapted to encircle the handle-bars of the bicycle and securely hold the carrier thereto, a buckle 9 being provided in each loop for conveniently attaching the carrier to or detaching the same from the bicycle. 75

In order to adjust the various straps to the 80 article to be carried, I provide each vertical loop-strap with two buckles 10 and 11, the buckles 10 being located in the front portion of the said straps between the two horizontal loop-straps and the buckle 11 being located 85 in the rear portion of the same, likewise between the two horizontal loop-straps. Each horizontal loop-strap is provided with two buckles 12 and 13, the buckles 12 being located in the rear portion of said loops between 90 the rear portions of the vertical loop-straps, and the buckles 13 being located in the front portion of the said loop-straps between the front portions of the vertical loop-straps. By means of the buckles 12 and 13 the size of the 95 horizontal loop-straps can be adjusted to fit the width or thickness of the article to be carried, and by means of the buckles 10 and 11 the distance between the two horizontal loop-straps, or between the upper horizontal loop- 100

strap and the lower end of the vertical loop-
straps, can be adjusted to fit the height of the
article to be carried.

As shown in Fig. 2, the lower horizontal
5 loop may be reduced in size to retain or sur-
round a small article supported on the lower
curved ends of the vertical loop-straps, and
the upper horizontal loop may be increased
10 in size to retain or surround a large article
supported on the lower horizontal loop.

As shown in Fig. 3, a bag 14 is held in the
carrier, wherein small articles may be con-
veniently carried in bulk.

To the rear face of the upper loop-strap a
15 retaining-clip 15 is riveted, said clip consist-
ing of a strip of metal bent between its ends
into a U-shaped portion 16, thence being bent
upon itself along the sides of said U-shaped
20 portion, as at 17, and finally terminating in
the lateral extensions 18, through which and
the strap of the upper loop the rivets 19 pass
to secure the clip to the carrier. This clip
embraces the steering-head and prevents lat-
er al movement of the carrier on the bicycle.

25 In Fig. 5 of the drawings I have shown the
carrier with the several adjusting - buckles
omitted.

In practice I have found leather straps to
be best adapted for this invention; but any
30 other material suitable for the purpose may
be used, if desired.

Having thus described my invention, what
I claim is—

35 1. A luggage-carrier comprising two ver-
tical open-loop straps, an upper and a lower
horizontal loop-strap secured to the said ver-
tical open-loop straps, and attaching-loops se-
cured to the upper horizontal loop-straps.

40 2. A luggage-carrier comprising two ver-
tical open-loop straps, means for adjusting the
same to conveniently support an article, two
horizontal closed loop-straps secured to said
vertical open-loop straps, and means for sup-
porting the carrier.

45 3. A luggage-carrier comprising two ver-
tical open-loop straps, means for adjusting the
loops in size to fit the article to be carried, two
horizontal closed loop-straps secured to said
vertical loop-straps, and means for adjusting
50 said horizontal loop-straps to any size.

4. A luggage-carrier comprising two ver-

tical loop-straps open at the top, a closed hori-
zontal loop-strap secured to the ends of said
vertical loop-straps, a second closed horizontal
loop-strap secured to said vertical loop-
55 straps between the lower ends thereof and the
first-mentioned horizontal loop-strap, a buckle
secured to each of said loop-straps whereby
the article to be carried may be conveniently
placed in the carrier and securely held. 60

5. A luggage-carrier comprising two ver-
tical loop-straps open at the top, a closed hori-
zontal loop-strap secured to the ends of said
vertical loop-straps, a second closed horizontal
loop-strap secured to said vertical loop-
65 straps between the lower ends thereof and the
first-mentioned horizontal loop-strap, two
buckles secured to opposite points of each
loop-strap, whereby the carrier may be ad-
justed in size in two directions to fit the ar-
70 ticle to be carried.

6. A luggage-carrier comprising two ver-
tical loop-straps open at the top, a closed hori-
zontal loop-strap secured to the ends of said
vertical loop-straps a second closed horizontal
loop-strap secured to said vertical loop-straps
75 between the lower ends thereof and the first-
mentioned horizontal loop-strap, and a clip
secured to the rear of the first-mentioned
horizontal loop-strap and adapted to embrace
80 the steering-head of a bicycle to prevent lat-
eral movement of the carrier thereon.

7. A luggage-carrier comprising two ver-
tical loop-straps open at the top, a closed hori-
zontal loop-strap secured to the ends of said
vertical loop-straps, a second closed horizontal
loop-strap secured to said vertical loop-straps
85 between the lower ends thereof and the first-
mentioned horizontal loop-strap, means to
permit of enlarging or lessening the size of
the horizontal loop-straps to the same or dif-
ferent sizes, whereby small articles may be
held by the second - mentioned horizontal
loop-strap and larger articles may be held by
90 the first-mentioned horizontal loop-strap. 95

In witness whereof I have affixed my signa-
ture in the presence of two subscribing wit-
nesses. •

FRANK SIMONS.
